UNITED STATES PATENT OFFICE

133,875

DESIGN FOR A WRAPPING PAPER OR SIMILAR ARTICLE

George C. Adams, New York, N. Y., assignor to The J. B. Williams Company, Glastonbury, Conn.,
a corporation of Connecticut

Application June 18, 1942, Serial No. 107,233

Term of patent 14 years

To all whom it may concern:

Be it known that I, George C. Adams, a citizen of the United States and a resident of New York city, in the county of Queens and State of New York, have invented a new, original, and ornamental Design for a Wrapping Paper or Similar Article, of which the following is a specification, reference being had to the accompanying drawing, forming part thereof, in which the figure is a face view of a wrapping paper or similar article showing my new design.

I claim:

The ornamental design for a wrapping paper or similar article, as shown.

GEORGE C. ADAMS.
